UNITED STATES PATENT OFFICE.

OSCAR KEEFER, OF NEW YORK, N. Y., ASSIGNOR OF TWO-THIRDS TO ISAAC LICHTENSTEIN,
OF NEW YORK, N. Y.

CENTRIFUGAL DRIER.

No. 922,149.

Specification of Letters Patent.

Patented May 18, 1909.

Application filed December 28, 1908. Serial No. 469,802.

To all whom it may concern:

Be it known that I, OSCAR KEEFER, a citizen of the United States, and a resident of the city, county, and State of New York, have invented a new and useful Improvement in Centrifugal Driers, of which the following is a specification.

The object of my invention is to provide a machine of this class which is adapted to receive hat bodies or bats and to dry the same by rapidly rotating them in the drier about a horizontal axis, and also to provide a suitable hood which will deflect the water thrown from the machine, and cause the same to be thrown into a well provided with a drain, whereby the water or other liquid thrown out by the centrifugal action of the machine will be prevented from spreading beyond the limits of the machine and will be collected within the compass of the machine and drained off. These objects are accomplished by my invention, one embodiment of which is described below.

For a more particular description of my invention, reference is to be had to the accompanying drawings forming a part hereof, in which:

Figure 1 is a perspective view of my improved machine. Fig. 2 is a side elevation of the same, a portion of the hood being elevated. Fig. 3 is an enlarged section of a portion of the drum, taken on the line 3—3 of Fig. 4. Fig. 4 is taken at right angles to Fig. 3. Fig. 5 is a cross section of my improved machine. Fig. 6 is an end elevation of the hood and the means for supporting the same.

Throughout the various views of the drawings, similar reference characters designate similar parts.

My improved drier 1, rests on a base 2 which is surrounded by an inclined well 3 which is adapted to receive the water which drains from a hood 4 surrounding the upper portion of the drier, the well 3 having a drain 3^a leading to any desired place. The hood 4 is supported by standards 5 secured to the base by screws or in any other suitable manner, and to the upper ends of these standards is secured the fixed section 6 of the hood 4. The movable section 7 is identical with the fixed section 6 except that it is hinged thereto as at 7^a, and may be raised as shown in Figs. 1 and 2 so as to permit the operator to attend to the drier. This hood 4 is shaped

substantially as shown, in the preferred embodiment of my invention, and extends sufficiently far to cause all water thrown against its interior to run to its lower edge and then drip into the well 3 from whence it is drained.

The centrifugal drier 1 is supported by standards 8 secured to the base 2 in any suitable manner, as by bolts or screws 9, and each standard 8 preferably consists of two converging legs united by a crossing at their lower ends and forming bearings 10 at their upper ends. Each of the bearings 10 is provided with the usual brasses 11, in which is journaled a shaft 12 in the conventional manner. One end of the shaft 12 extends through the hood 4 and is provided with suitable pulleys 13, fixed thereto, by means of which it may be rotated and on the outer sides of the bearings 10, this shaft 12 is provided with collars 14 fixed thereto, which prevents any end play of the shaft. This shaft 12 also carries a drum 15 formed with heads 16, fixed on the shaft 12, and united near their peripheries by means of tie-bolts 17 fixed by nuts 18 on each side of the disks 16. These disks may be readily removed from the shaft 12 by withdrawing the keys 19 by which they are held and also by removing the tie-bolts 17. The heads 16 and the bolts 17 are preferably made of some metal which will not corrode or else covered with a non-corrosive coating. The bolts 17 arranged as shown, do not extend the entire circumference of the disks 16 but leave a suitable gap, as shown, having a door 20 which is hinged to one of the bolts 17 and provided with a perforated lug 21 on the opposite side which is adapted to be held by a thumb screw 22, as shown. This construction permits the drum 15 to be opened or closed at the volition of the operator.

From the foregoing the operation of my improved drier will be readily understood. Assuming the parts to be as shown in Fig. 1 the bats or other articles to be dried are inserted and the door is then closed as indicated in Fig. 2. The hood is then closed by having its part 7 lowered and the drum 15 is then rotated by any suitable means, not shown, at a high velocity, so that all liquid is thrown to the interior of the hood 4 and drains from its lower edge as described above. In a few minutes, after centrifugal force has removed all moisture from bats power is thrown off, the part 7 of the hood is raised, the door 20 is

opened and the dry bats removed and wet ones inserted when the operation is repeated as before.

While I have shown and described one embodiment of my invention, it is obvious that it is not to be considered as restricted thereto, but is broad enough to cover all structures that come within the scope of the annexed claims.

10. What I claim is:—

1. A centrifugal drier composed of a shaft and means for mounting the same so that it can be rotated, disks on said shaft and tie bolts joining said disks for a portion only of the periphery thereof, and a hood in sections with the joint in vertical alinement with said shaft a door secured to some of said tie bolts and closing the gap between said tie bolts.

2. In a machine of the class described, a shaft and means for mounting the same so that it can be rotated, disks secured to said shaft, tie bolts uniting said disks, a door secured to some of said tie-bolts, and a hood

divided longitudinally along its central line, with a movable portion adapted to cover said drum.

3. In a machine of the class described, a shaft and means for mounting the same so as to permit rotation thereof, a drum mounted on said shaft composed of a pair of disks 30 united by tie-bolts extending for a portion only of the periphery of said disks, and a door uniting some of said tie-bolts and closing the gap between said tie bolts, a hood covering said drum having one portion hinged in vertical alinement with the axis of said drum and a well below the lower edge of said hood adapted to receive water draining from the same.

Signed at New York city, New York, this 40
28th day of December, 1908.

OSCAR KEEFER.
